UNITED STATES PATENT OFFICE.

CHARLES H. HASBROUCK, OF BINGHAMTON, NEW YORK.

MACHINE FOR PROTECTING CHECKS AND THE LIKE.

1,296,511.

Specification of Letters Patent.

Patented Mar. 4, 1919.

Application filed November 27, 1917. Serial No. 204,210.

To all whom it may concern:

Be it known that I, CHARLES H. HASBROUCK, a citizen of the United States, and a resident of Binghamton, in the county of 5 Broome and State of New York, have invented new and useful Improvements in Machines for Protecting Checks and the like, of which the following is a specification.

This invention relates to machines for 10 protecting checks and the like.

An important object of the invention is to provide in a device of the above mentioned character a means whereby a maximum speed in the operation of the device as a 15 whole may be attained.

A further object of the invention is to provide in a device of the above mentioned character a means whereby a uniform spacing between the several characters, when 20 transferred upon the face of a check or the like, may be easily and effectively attained.

A further object of the invention is to provide in a device of the above mentioned character a means whereby selected indicia 25 may be easily and effectively brought into printing position.

A further object of the invention is to provide in a device of the above mentioned character a means whereby the selected indicia, when brought into printing position, may be effectively held in the desired position during the printing operation of the same.

A further object of the invention is to 30 provide in a device of the above mentioned character a means whereby the various working elements employed in the device may be actuated with the least possible amount of friction and noise.

A further object of the invention is to 35 provide in a device of the above mentioned character a means whereby the check or other document desired to be operated upon may be positively and effectively guided in 40 its course of travel into and through the device when undergoing the printing operation thereupon.

A further object of the invention is to 45 provide a device of the above mentioned character which is simple in construction, strong, durable, reliable in operation, and inexpensive to manufacture.

Other objects and advantages of the invention will be apparent during the course 50 of the following description.

Common subject matter which is shown

and described in this application but not claimed herein is claimed in my copending applications for machines for protecting checks and the like; one case filed August 1, 60 1916, Serial No. 112,539 and the other being filed March 3, 1917, Serial No. 152,425.

In the drawings, forming a part of this specification and in which like numerals are employed to designate like parts throughout the same,

Figure 1 is a horizontal sectional view of a device embodying my invention, certain elements being shown in plan,

Fig. 2 is a fragmental view of the same 70 showing the position of a scale positioned thereon,

Fig. 3 is a vertical longitudinal sectional view taken on the line 3—3 of Fig. 1,

Fig. 4 is a vertical longitudinal sectional 75 view of Fig. 1 taken on the line 4—4,

Fig. 5 is a detail sectional view taken on the line 5—5 of Fig. 11,

Fig. 6 is a vertical longitudinal sectional view taken on the line 6—6 of Fig. 1, 80

Fig. 7 is a transverse central section taken on the line 7—7 of Fig. 1,

Fig. 8 is a transverse sectional view taken on the line 8—8 of Fig. 1,

Fig. 9 is a sectional view taken on the 85 line 9—9 of Fig. 1,

Fig. 10 is a detail transverse sectional view taken on the line 10—10 of Fig. 8,

Fig. 11 is a transverse sectional view taken on the line 11—11 of Fig. 1, 90

Fig. 12 is a similar view of the same showing a check or other document undergoing a printing operation, and,

Fig. 13 is a detail fragmental sectional 95 perspective view of a portion of a printing wheel.

In the drawings, wherein for the purpose of illustration is shown a preferred form of my invention, the numeral 15 indicates a base, a portion of which is depressed as 100 shown at 16 to form a guide or passage indicated by the numeral 17, the purpose of which will be hereinafter described. The under side of the base 15 is provided with a lug 18 to which is secured a spring member 19 by means of a screw or the like as shown at 20. This spring member is provided at an appreciable distance from its free end with a substantially U-shape frame 21 having journaled therein a platen wheel 110 22 adapted to extend through an opening 23 provided by the depressed portion 16 of the

base 15. The spring member 19 is provided at the end thereof with an opening, as shown, adapted to receive therein the depending end of a screw-threaded shank 5 which is secured to the base 15 as shown. A thumb-wheel 19' is carried by the screw-threaded shank and adapted for vertical adjustment thereon and serves as a means for vertically adjusting the platen wheel 22 10 within the opening 23 through the instrumentality of the spring member 19 as is apparent from the disclosure shown in Fig. 12 of the accompanying drawings.

Upon the base 15 there is disposed a plate 15 24 which is secured thereto by means of screws or the like as shown at 25 and provided at one longitudinal edge thereof with a vertically disposed wall 26. This wall is provided substantially centrally therein with 20 an opening 27 through which a shaft 28 is adapted to be passed. This shaft is substantially square in cross section as shown in Fig. 6 and has secured at one end thereof a drum 29. This drum it will be noted is provided with flanges 30, the intermediate one of which serves to divide the face of the drum into two equal portions, 31 and 32, as shown. It will be further noted that the drum 29 is depressed at one side thereof, 30 within which depression there is disposed a tension adjusting means, indicated as a whole by the numeral 33, which comprises a plate 35 journaled upon a hub 36 of the drum 29 and clearly shown in Figs. 3 and 35 11. Upon one face of the plate 35 there is disposed a pin or lug 37, while upon the other face there is disposed a similar lug or pin 38, adapted to project through an opening 39 provided within the drum 29 as clearly shown in Figs. 3 and 5. To the lug 37 there is secured an end 40 of a flexible metallic band 41 which is passed around that portion of the drum 29 indicated by the numeral 31, and through an opening 42 40 provided therein as clearly shown in Fig. 3. This flexible metallic band 41 is adapted to be passed over a pair of guide rollers 43, journaled to the wall 26 as shown at 44. The other end of this metallic belt 41 is 45 passed over that portion of the drum 29 indicated by the numeral 32, and through a slot 45 provided therein as clearly shown in Fig. 5, whereupon the same is secured to the lug or pin 38 as clearly shown in Fig. 5. 55 The plate 35 is provided with an arcuate-shape slot 46, through which a screw 47 is adapted to be passed and maintained in screw-thread engagement with the drum 29, as clearly shown in Fig. 11. It may be readily seen, when considering Fig. 3, that by moving the plate 35 in a clockwise direction, with respect to the drum 29, the tension of the metallic band 41 may be increased, and, by moving the plate 35 in an anti-clockwise 60 direction with respect to the drum 29, that

the tension of the metallic band 41 may be decreased. When the desired degree of tension has been obtained within the band 41 by adjusting the plate 35, as described, the screw 47 may be tightened thereupon, thereby retaining the same in the desired position. A portion of the vertically disposed wall 26 is bent at right angles with respect to the same, as shown at 48, thereby providing supports for a guide rod 49 secured therebetween by means of screws or the like as shown at 50. Upon this guide rod there is slidably mounted a sleeve 51 provided at the lower edge thereof with a depending L-shape member 52, carrying therein a set-screw or the like, as shown at 53, adapted to secure the sleeve 51 as a whole, to the metallic band 41 at any desired point thereon. To one face of the sleeve 51 there is secured a handle 54, the outer end of which is provided with a suitable grip 55. This handle is provided with a substantially L-shape pointer 56 adapted to function, as will hereinafter be described in connection with a dial 57 carried by a cover 58 inclosing the various working elements of the device as is readily understood from the accompanying drawings. 70 75 80 85 90 95

Upon the plate 24 there is disposed an I-shape supporting guide 59, the base of which is secured to the plate 24 by means of screws or the like as shown at 60. The head of this I-shape supporting guide is provided with a pair of parallel grooves 61 and 62, they being divided by a tongue 63 as clearly shown in Figs. 9 and 10. It will be noted that one end of the tongue 63 is provided with a bevel face as shown at 64. Upon the upper face of the head of the I-shape supporting guide there is disposed a spring 65 which is secured thereto by means of a screw 66. It will be noted that one end of the spring 65 is bent to a substantial U-shape as shown at 67 while the other end of the spring is bent to a U-shape as 100 shown at 68, the last mentioned U-shaped portion being substantially larger than that shown at 67. Both of the U-shaped portions 67 and 68 function as a shock absorbing means which will hereinafter be described when considering the operation of the device as a whole. To one face of the supporting guide 59 there is secured a screw 69 about which is coiled a spring member 70, one end of which engages a lug 71 while the other end is adapted to normally maintain the position shown in Fig. 8. To the plate 24 there is secured an upright supporting member 72, carrying one end of a guide rod 73, the other end of which is secured by a 105 screw to the vertically disposed wall 26 as shown at 74. Mounted upon and carried by the guide rod 73 is a transversely movable frame 76, having side members 77 and 78 through which the shaft 28 is adapted to 110 115 120 125 130

pass between the side members 77 and 78. Upon the shaft 28 there is slidably mounted a journal bearing 79, the interior of which is substantially square in cross section as best shown in Fig. 11. Fixedly carried by the journal bearing 79 is a printing wheel indicated as a whole by the numeral 80, which comprises a hub 81, carrying at one end thereof a web 82, the periphery of which is provided with a plurality of spaced printing blocks 83, provided with raised faces, as shown at 84, upon which are formed suitable printing characters as clearly shown in Fig. 13. In order to prevent the printing wheel 80 from rotating upon the journal bearing 79 there is provided a set-screw 84 passed through the hub 81 and adapted to engage the journal bearing 79 as shown in Figs. 11 and 12. It will be noted that the lower portion of this printing wheel is adapted to extend through an opening 81' provided within the plate 24 in order to permit the printing blocks 83 to normally engage the platen wheel 22, which engagement is clearly illustrated in Fig. 6.

To the outer face of the side members 77 there is secured an L-shape supporting member 85, the upper end 86 of which carries a substantially arcuate-shape, preferably resilient, roller supporting member 87 which is held in engagement with the upper end of the L-shape supporting member by means of a screw or the like as shown at 88. Each end of this roller supporting member is provided with a substantially U-shape frame 89 having journaled therein an inking roller 90.

To one end of the frame 76 there is secured a supporting pin 91 the outer end of which is adapted to reciprocate within the grooves 61 and 62 as will be apparent when considering the hereinafter described operation of the device as a whole.

In order to retain the frame 76 normally in the position shown in Figs. 1, 7 and 11 there is provided a coil spring 92, one end of which is secured to an arm 93 carried by the side member 77 of the frame 76, while the other end is secured to an eyelet 94 carried by the vertically disposed wall 26.

Upon one end of the plate 24 there is disposed an L-shape bracket 95 which is secured thereto by means of screws or the like as shown. To this bracket there is secured a bell crank lever 97, one arm of which is provided with an elongated slot 98 while the other arm is provided with a similar elongated slot 99. An operating handle 100 is pivotally secured to the bracket 95 as shown at 101. This arm is provided with a pin 102, adapted to be passed through and reciprocate within the slot 98. A pin 103 is carried by one end of the frame 96 and is adapted for reciprocatory movement within the slot 99.

A vertical support 104 is secured to the

metal plate 24 and provided with a horizontally extending pin 105 which is adapted to enter the openings formed between the printing blocks 83 when the printing wheel 80 is moved to the position clearly shown in Fig. 12. It will be noted that each of the printing blocks 83 is provided with bevel faces 106 which serve as means for guiding the pin 105 into the openings between the blocks 83 should the openings, accidentally or otherwise, be moved out of perfect alignment with the pin when the printing wheel 80 is being moved in the direction indicated by the arrow shown in Fig. 12.

To the outer face of the vertically disposed wall 26 there is pivotally connected an arm 107 by means of a screw or the like as shown at 108. Through the lower end of this arm there is passed an adjustable rod 109 adapted to be maintained at a desired position by means of a set-screw 110. One end of the rod 109 is provided with a rotatable spur wheel 111 adapted to engage and guide a check or other document indicated by the numeral 112 in its course of travel through the device as shown in Fig. 12. In order to maintain engagement of the spur wheel 111 with the check or other document 112 there is provided a coil spring 113 one end of which is secured to the rod 109 as shown in Fig. 3. It might be well for me to state here that the spur wheel 111 may be axially disposed at right angles to the course of travel of the check 112, or set at a sufficient angle to create a tendency to thrust the check toward a guide flange 113, carried by a table 114 slidably mounted upon a rod 115, supported by brackets 116 which are secured to the base 15 as shown in Fig. 7. This table is provided with a pair of ears 117 through which the rod 115 is passed, one of these ears being bent to a substantial U-shape as shown at 118. A guide 119 is disposed within the guide or passage 17 and is provided with a depending partition 120 which is mounted upon the rod 115 and carried between the side arms of the U-shape portion 118.

In use, the operation of the device is as follows: Should it be desired to print a check or other document the handle 54, passed through an elongated slot 58' provided within the cover 58, is moved longitudinally to bring the pointer 56 opposite a desired character carried by the dial 57, whereupon the printing wheel 80 is moved, rotatably through the instrumentality of the belt 41, to such a position as will bring into printing position a printing character corresponding to the character opposite the pointer 56. The check or other document is then inserted into the passage 17 allowing one edge to contact with the guide 119, carried therein, and the flange 113 carried by the table 114. The table 114 together with

the guide 119 is then moved upon the rod 115 to such a position as will bring that portion of the check upon which the characters are desired to be printed directly over 5 the platen wheel 22. The lever 100 is then moved downwardly through an elongated slot 100' provided within the cover 58, thereby moving the frame 76 through the instrumentality of the bell crank lever 97, in the 10 direction indicated by the arrow of Fig. 12, whereupon the pin 105 will enter one of the openings provided between a pair of printing blocks 83, as shown in Fig. 12, in order to prevent the printing wheel 80 from revolving 15 during its longitudinal movement upon the shaft 28. When the printing wheel 80 has been moved a sufficient distance, the raised portion 84 of the printing block 83 is brought into engagement with the check 20 or other document placed upon the platen wheel 22 as hereinbefore described. By continuing the movement of the printing wheel 80 in the direction of the arrow shown in Fig. 12 the supporting pin 90 is brought out 25 of engagement with the slot 62 and under the influence of the spring 70 is elevated to the position shown in Fig. 9, striking upon the U-shape portion of the spring 65, as shown at 67, which U-shape portion is designed 30 to absorb the shock and dampen the noise which would otherwise be created by the striking of the supporting pin when being elevated as described. Due to the fact that the supporting pin 91 is elevated as 35 hereinbefore described the frame 76 carrying the printing wheel 80 is necessarily swung upwardly upon the guide rod 73 thereby releasing the printing block 83 from the face of the document or check. The frame 76 is moved under the influence of 40 the spring 92 to the position shown in Figs. 7 and 11, allowing the check or other document to be freely removed from within the device should it be so desired. It might be 45 well for me to state here that immediately upon the return of the frame 76 to its normal position the supporting pin 91 passes out of the slot 61 through which it travels when being moved to its normal position as 50 before described and drops under the weight of the frame 76 to the position shown in Fig. 8, striking upon the U-shape portion of the spring 65 indicated at 68, which U-shape portion absorbs any shock or noise, due to 55 the sudden drop, which would otherwise be created. In order to counteract the tendency of the shaft 28 to move in the direction of travel of the printing wheel when it is returning to its normal position there is provided 60 a wear washer 28' which is secured to the inner face of a side of the cover 58 by any suitable means and adapted to normally engage the end 29' of the shaft 28 as clearly shown in Figs. 11 and 12. Should it be 65 desired to print another character upon the

check before the same is removed from within the device the same operation as hereinbefore described is repeated.

The spacing of the printed words or characters is a highly important factor in a machine of the character described and is accomplished, for example, in the following manner. Since the check or work 112 is fed into the machine by the contact of the printing wheel 80 with the coöperating platen 70 wheel 22 the length of travel of the check for a single printing operation depends upon the point on the platen wheel at which the printing wheel comes into contact therewith. Should the platen wheel 22 be lowered with 80 respect to the printing wheel 80 by means of the thumb screw 19', the printing wheel would contact with the platen wheel nearer the top thereof, therefore the space between the characters or words printed would be 85 diminished. On the other hand, should the platen wheel 22 be raised with respect to the printing wheel 80 the space between the characters printed would be increased.

It is to be understood that various changes 90 in the shape, size and arrangement of parts may be resorted to without departing from the spirit of my invention or the scope of the subjoined claims.

Having thus described my invention, what 95 I claim as new and desire to secure and protect by Letters Patent of the United States, is:

1. In a device of the character described, a base, a pivoted and transversely movable frame mounted thereon, a type wheel mounted in a frame, a platen wheel mounted on the base, means for bringing the character of the type wheels selectively into alinement with the platen, and means for shifting the type wheel across the platen.

2. In a device of the character described, a base, a pivoted and transversely movable frame mounted thereon, a type wheel mounted in the frame, a platen to coöperate 110 with the type wheel, means for bringing the characters of the type wheel selectively in alinement with the platen and shifting the type wheel across the platen, means raising the type wheel after the printing 115 operation, and means for returning the type wheel to its normal position.

3. In a device of the character described, a base, a supporting member mounted thereon, a frame pivoted and transversely 120 movable thereon, a type wheel mounted in the frame, a platen coöperating with the type wheel, means for bringing the characters of the type wheel selectively in alinement to coöperate with the platen, means for shifting the type wheel to bring its characters into engagement with the platen, and a spring urging the frame to its normal position.

4. In a device of the character described, 125

a base, a supporting member mounted thereon, a frame pivoted and transversely movable thereon, a type wheel mounted in the frame and a platen coöperating with the type wheel, means for bringing the characters of the type wheel selectively in alinement with the platen, and a lever adapted to shift the frame, whereby the type wheel is moved in printing engagement with the platen.

5. A device of the character described comprising a shaft, a drum secured to the shaft, a plurality of guide rollers, a flexible belt passed over the guide rollers and having its ends secured to the drum, a printing wheel movably mounted upon said shaft, a platen wheel arranged in proximity to the printing wheel, manually operated means for horizontally moving the printing wheel into engagement with and over the platen wheel, means for disengaging said printing wheel and platen wheel subsequent to the engagement therebetween, and means for returning the printing wheel 25 to a normal position subsequent to the disengagement of the same from said platen wheel.

6. A device of the character described comprising a shaft, a drum secured to the shaft, a plurality of guide rollers, a flexible belt passed over the guide rollers and having its ends secured to the drum, a printing wheel movably mounted upon said shaft, a platen wheel arranged in proximity to the printing wheel, manually operated means for horizontally moving the printing wheel into engagement with and over the platen wheel, means for disengaging said printing wheel and platen wheel subsequent to the engagement therebetween, means for returning the printing wheel to a normal position subsequent to the disengagement of the same from said platen wheel, and means for maintaining the printing wheel disengaged from said platen wheel during the return movement of the printing wheel to normal position.

7. In a device of the character described a shaft, a printing wheel slidably mounted thereon, a platen wheel, a drum secured to the shaft, a plurality of guide rollers, a belt passed over the rollers and having its ends secured to the drum, means for varying the tension of the belt, and means for 55 moving the printing wheel into engagement with and over the face of the platen wheel.

8. In a device of the character described a shaft; a printing wheel slidably mounted thereon; a platen wheel; a drum secured to the shaft; a plurality of guide rollers; a belt passed over the rollers and having its ends secured to the drum; means for varying the tension of the belt, said means comprising a movable plate provided with a 65 plurality of pins having the ends of said

belt attached thereto and a screw for retaining the plate in a desired position; and means for moving the printing wheel into engagement with and over the face of the platen wheel.

9. In a device of the character described a horizontally movable frame, a shaft extending therethrough, a printing wheel carried by the shaft and mounted within said frame, a platen wheel, manually operable means for horizontally moving the frame together with the printing wheel whereby the periphery of the printing wheel is brought into engagement with the face of the platen wheel, a drum secured to the shaft, a plurality of guide rollers, a metallic belt passed over the guide rollers and having its ends attached to the drum, and a spring for returning the printing wheel and frame to a normal position.

10. In a device of the character described, a horizontally movable frame, a shaft extending therethrough, a journal bearing slidably mounted upon the shaft and journaled within the frame, a printing wheel secured to the bearing, a platen wheel, manually operable means for horizontally moving the frame together with the printing wheel whereby the periphery of the printing wheel is brought into engagement with and over the face of the platen wheel, a drum secured to the shaft, a plurality of guide rollers, a metallic belt passed over the guide rollers and having its ends attached to the drum, and a spring for returning the printing wheel to a normal position.

11. In a device of the character described, a base, a pivoted and transversely movable frame mounted thereon, a type wheel mounted in the frame, a platen wheel, means for bringing the characters of the type wheel selectively into alinement with the platen wheel, means for moving the printing wheel into engagement with and over the face of said platen wheel, and means for lifting the printing wheel out of engagement with the platen wheel subsequent to the engagement therebetween.

12. In a device of the character described, a guide rod, a horizontally movable frame mounted upon the rod, a shaft extending through the frame, a printing wheel slidably mounted upon the shaft, manually operable means for moving the frame in one direction, a spring for moving the frame in the opposite direction, a supporting guide having a pair of horizontal grooves provided therein, and a supporting pin carried by the frame and adapted to traverse one of said grooves when the frame is moved in one direction and the other of said grooves when the frame is moved in the opposite direction.

13. In a device of the character described,

- 6 a base, a pivoted and transversely movable frame mounted thereon, a type wheel mounted in the frame, a platen wheel, means for moving the character of the type wheel into engagement with and over the face of the platen wheel, yielding means for returning the printing wheel to normal position, means for lifting the printing wheel out of engagement with the platen wheel subsequent to its passing thereover, and means for retaining the printing wheel out of engagement with the platen wheel during the return movement of the printing wheel to a normal position. 70
- 10 15. 14. In a device of the character described, a horizontally movable printing wheel; manually operable means for moving the printing wheel into engagement with and over the face of the platen wheel whereby the work is fed between the printing wheel and platen wheel, means for frictionally engaging the work in its course of travel, the last mentioned means comprising a rod having a spur wheel rotatably mounted thereupon; an adjustable table to support the work when being fed; and a guide for guiding the work during its passage between the printing wheel and platen wheel. 75
- 20 25. 15. In a device of the character described, a base, a pivoted and transversely movable frame mounted thereon, a type wheel mounted in the frame, said type wheel being provided with printing blocks, a platen wheel, means for moving the printing blocks successively into engagement with and over the face of the platen wheel whereby work may be fed between the platen wheel and the printing wheel to receive thereupon the imprint of printing character carried by selected printing blocks, means for varying the space between the imprint of one set of characters carried by one printing block and the second set of characters carried by the second printing block, and means for lifting the printing wheel from the platen wheel subsequent to its engagement therewith. 80
- 30 35. 16. In a device of the character described, a platen wheel, a guide rod, a horizontally movable frame mounted upon the rod, a shaft extending through the frame, a printing wheel mounted upon the shaft, manually operable means for moving the frame together with the printing wheel in one direction with respect to said shaft whereby said printing wheel is moved into engagement with and over the face of the platen wheel, means for returning the frame together with the printing wheel to a normal position, means for lifting the printing wheel out of engagement with the platen wheel subsequent to the engagement therebetween. 85
- 40 45. 17. In a device of the character described, a platen wheel, a guide rod, a horizontally movable frame mounted upon the rod, a shaft extending through the frame, a printing wheel mounted upon the shaft, manually operable means for moving the frame together with the printing wheel in one direction with respect to said shaft whereby said printing wheel is moved into engagement with and over the face of the platen wheel, means for retaining the printing wheel in engagement with the platen wheel during the passage of the printing wheel thereover, means for lifting the printing wheel out of engagement with the platen wheel subsequent to its passage thereover, and means for retaining the printing wheel disengaged from the platen wheel subsequent to the passage of the printing wheel over the platen wheel, and means for retaining the printing wheel out of engagement with the platen wheel during the return movement of the printing wheel to a normal position. 90
- 50 55. 18. In a device of the character described, a platen wheel, a guide rod, a horizontally movable frame mounted upon the rod, a shaft extending through the frame, a printing wheel mounted upon the shaft, manually operable means for moving the frame together with the printing wheel in one direction with respect to said shaft whereby said printing wheel is moved into engagement with and over the face of the platen wheel, means for retaining the printing wheel in engagement with the platen wheel during the passage of the printing wheel thereover, means for lifting the printing wheel out of engagement with the platen wheel subsequent to its passage thereover, and means for retaining the printing wheel disengaged from the platen wheel subsequent to the passage of the printing wheel over the platen wheel, and means for retaining the printing wheel out of engagement with the platen wheel during the return movement of the printing wheel to a normal position. 95
- 60 65. 19. In a device of the character described, a platen wheel, a guide rod, a horizontally movable frame mounted upon the rod, a shaft extending through the frame, a printing wheel mounted upon the shaft, manually operable means for moving the frame together with the printing wheel in one direction with respect to said shaft whereby said printing wheel is moved into engagement with and over the face of the platen wheel, means for retaining the printing wheel in engagement with the platen wheel during the passage of the printing wheel thereover, means for lifting the printing wheel out of engagement with the platen wheel subsequent to its passage thereover, and means for retaining the printing wheel disengaged from the platen wheel subsequent to the passage of the printing wheel over the platen wheel, and means for retaining the printing wheel out of engagement with the platen wheel during the return movement of the printing wheel to a normal position. 100
- 70 75. 20. In a device of the character described, a guide rod, a horizontally movable frame mounted upon the rod, a shaft extending through the frame, a printing wheel slidably mounted upon the shaft, manually operable means for moving the frame in one direction, a spring for moving the frame in the opposite direction, a supporting guide having a pair of horizontal grooves provided 105

therein, and a supporting pin carried by the frame and adapted to traverse one of said grooves when the frame is moved in one direction and the other of said grooves when the frame is moved in the opposite direction, means for directing the supporting pin into one of said grooves when the frame is moved in one direction, and means for directing the pin into the other of said grooves when the frame is moved in an opposite direction.

21. In a device of the character described, a rotatable and horizontally movable printing wheel provided with a plurality of spaced printing blocks carrying printing characters thereon, means for bringing the characters selectively into printing position, a platen wheel arranged in proximity to the printing wheel, means for horizontally mov-

ing the printing blocks successively into engagement with and over the face of the 20 platen wheel whereby work may be fed between the platen wheel and the printing wheel and imprint thereupon printing characters carried by selected printing blocks, means for automatically spacing the imprint of a set of characters carried by one printing block from the print of a succeeding set of characters carried by a second printing block, means for preventing rotation of the printing wheel during the horizontal movement of the same, and means for lifting the printing wheel from the platen wheel subsequent to its engagement with the platen wheel.

CHARLES H. HASBROUCK.
